UNITED STATES PATENT OFFICE.

JAMES H. COOPER, OF DETROIT, MICHIGAN, ASSIGNOR, BY MESNE ASSIGNMENTS, TO
McCORD RADIATOR & MFG. CO., OF DETROIT, MICHIGAN, A CORPORATION OF
MAINE.

VENT-TUBE-ATTACHING MEANS FOR RADIATORS.

Application filed November 2, 1922. Serial No. 598,493.

To all whom it may concern:

Be it known that I, JAMES H. COOPER, a subject of the King of Great Britain, residing at Detroit, in the county of Wayne and 5 State of Michigan, have invented new and useful Improvements in Vent-Tube-Attaching Means for Radiators, of which the following is a specification.

This invention relates to radiators for 10 motor vehicles.

The object of my invention is to provide means whereby the upper end of a vent tube may be readily and easily connected with the inside of a filler neck without the 15 use of solder as heretofore, and gain a connection which will not become loose and broken in service, and further leave open the upper end of the vent tube by having no solder to run over and partially or completely close said tube, as heretofore.

In the accompanying drawings illustrating my invention—

Fig. 1 is a front view of an assembled radiator wherein the upper end of the vent tube is attached to the filler neck in accordance with my invention;

Fig. 2 is an enlarged vertical sectional view taken through the filler neck and showing in detail the manner in which the vent 30 tube is attached thereto;

Fig. 3 is a top plan view of the structure shown in Fig. 1; and

Fig. 4 is a top plan view of the same parts with the fastening tongue shown in 35 position before it is bent to receive the vent tube.

The radiator shown in Fig. 1 has a core 1 contained within an outer metal shell or casing 2. These parts are made and assembled in accordance with the usual radiator practice. The core, through which the cooling water circulates, has the usual upper and lower tanks and the interposed water conduits, either corrugated when of the cellular type or in the form of vertical tubes when of the fin and tube type. It is immaterial to my invention whether the core is of one type or the other, although for illustrative purposes I have shown the fin and tube type in the drawings. The upper tank 3 is shown in Fig. 2, while the vertical tubes 4 and horizontal fins 5 are shown in 50 Fig. 1.

The radiator has a filler neck 6 secured to 55 the top of the upper tank 3 and opening

into the same. This neck extends upward through a hole 7 in the top wall of the shell 2, as shown in Fig. 2, and as usual in structures of this kind. To close the upper end of the neck 6 there is the usual screw-threaded cap 8.

The vent tube 9 has its upper end extending into the neck 6, as clearly shown in Fig. 2. This tube contacts against the inner surface of the neck 6 and said neck is provided with a depending, laterally narrow tail piece or tongue 10, which fits in the tube 9 to hold the tube against the filler neck. By pinching the tongue 10, the tube 9 is brought into firm contact with the neck 6 and held tightly in place.

The tongue 10 is carried by the filler neck 6, as shown, and provides a construction whereby the upper end of the tube 9 is permanently attached to the neck 6 without the use of solder as heretofore. Said tongue 15 makes a connection which will not become loose and broken when the radiator is in service as with solder joints, nor is the upper end of the tube 9 partially or fully closed by the solder running over as heretofore. With my connection the tube 9 is maintained open at all times and allowed to function properly as intended.

The tongue 10, as shown in the drawings, is made integral with the upper edge of the neck 6. This is done in the blanking or punching out of the center of the stamping from which the neck 6 is made. As shown in Fig. 4, the tongue 10 in the operation of blanking or stamping out the neck 6 is left integral with the upper edge of the neck and extends diametrically across the same. The second operation in making the neck consists in throwing down the tongue parallel with the wall of the neck so as to be in position to allow the vent tube to be slipped over the tongue and be clamped by pinching, as above suggested.

While I have shown and described herein 100 in detail a vent tube attaching means embodying the features of my invention, it is of course to be understood that the details of construction and arrangement of parts illustrated may be variously changed and modified without departing from the spirit and scope of my invention.

I claim as my invention:

1. A radiator for motor vehicles, comprising a core, a filler neck therefor, a vent tube 110

having its upper end in said neck, and means carried by said neck and engaging said tube through an opening therein for holding the tube in said neck.

5. 2. A radiator for motor vehicles, comprising a core having a filler neck, a vent tube having its upper end in said neck, and means carried by said neck and extending into said tube through its upper open end for holding

10 said tube in said neck.

3. A radiator for motor vehicles, comprising a core, a filler neck therefor, a vent tube in said core and having its upper end in said neck, a tongue integrally connected with said

15 neck above the upper end of said tube and extending downward into the latter for

holding the tube against the inside of said neck.

4. A radiator for motor vehicles, comprising a core, a filler neck therefor, a vent tube 20 having its upper end in said neck, and a tongue formed integral with the upper edge of said neck in the making of the same, said tongue being bent downward substantially parallel with the wall of said neck and extending into said tube and engaging the same for holding the tube against the inside 25 of said neck.

In testimony that I claim the foregoing as my invention, I affix my signature this 30 thirtieth day of October, A. D. 1922.

JAMES H. COOPER.
